UNITED STATES PATENT OFFICE

EDGAR A. LEHMAN, OF CANNELTON, INDIANA, ASSIGNOR TO THE LEHMAN COMPANY OF AMERICA, OF CANNELTON, INDIANA, A CORPORATION OF INDIANA

DESIGN FOR A SWING

Application filed December 30, 1931. Serial No. 42,317. Term of patent 7 years.

To all whom it may concern:

Be it known that I, EDGAR A. LEHMAN, a citizen of the United States, residing at Cannelton, in the county of Perry and State of Indiana, have invented a new, original, and ornamental Design for a Swing, of which the following is a specification, reference being had to the accompanying drawing, forming a part hereof.

The single figure is a perspective view of a swing showing my new design.

I claim:

The ornamental design for a swing, as shown.

EDGAR A. LEHMAN.
